UNITED STATES PATENT OFFICE.

CHARLES F. GREGG, OF INDIANAPOLIS, INDIANA.

DRYING MACHINE.

Application filed March 18, 1926. Serial No. 95,612.

My invention relates to improvements in drying machines particularly for use in cleaning establishments.

In the methods heretofore used in commercial cleaning establishments for the drying of clothes, the garments having been cleaned in the "washer" are withdrawn and centrifuged; then passed to a drying tumbler of the rotary oscillating type and the clothes are therefore subjected to considerable rough usage due to the tumbling.

Another method now commercially used is that of hanging the clothes in a drying room which is heated. One of the objections to the first method is that delicate fabrics, etc., due to the rough tumbling in the tumbler are frequently injured and destroyed and one of the objections to the second method of drying is the time required in hanging the garments and taking them down after drying and the space required for a drying room.

It is one of the objects of my invention to provide a drying apparatus in which delicate fabrics may be readily dried by having currents of air passed therethrough and at the same time being slightly moved to permit the free passage of the air without rough tumbling.

For the purpose of disclosing my invention I have illustrated one embodiment in the accompanying drawings in which

Fig. 1 is a side elevation of an apparatus embodying my invention;

Fig. 2 is a transverse sectional view;

Fig. 3 is a longitudinal sectional view, and

Fig. 4 is a bottom side elevation partly in section showing means for delivering heated air to the drying apparatus.

In the embodiment illustrated I provide a housing or casing 1 preferably cylindrical in shape having a cone shaped bottom 2 provided at the apex of the cone with an air inlet opening 3. This casing near its top is provided with an exit opening 4 and with a suitable door 5 to permit access to the interior thereof. Vertically reciprocating within this casing is a receptacle 6 cylindrical in shape and having a cone shaped

bottom 7 open at its lower end, the opening being covered however by foraminous material 8. This receptacle is adapted to receive the articles to be dried and to prevent the escape of the articles during the drying

operation I provide a foraminous cover in the form of a pair of hinged sections 9 and

10 adapted to be held closed by a suitable latch 11. This receptacle 6 substantially fits the casing 1, only sufficient space being allowed between the walls of the two to permit ready movement of the receptacle. This spacing is closed by an annular packing ring 12 mounted on the receptacle 6 and making sliding engagement with the inner wall of the casing 1.

The casing 1 is supported above the floor on suitable legs 13 formed in pairs and each pair being connected by an arcuate cross member 14 by which the legs are secured to the casing.

For reciprocating the receptacle 6 in the casing the receptacle is provided with a pair of vertically extending arms 15 provided at their tops with horizontal extensions 16 arranged to project through suitable slots in the sides of the casing and provided with sockets 17 arranged to receive the upper ends of sliding rods 18, these being guided in guide sockets 19 secured on the exterior of the casing. The rods 18 have secured thereto pitman rods 20 connected at their lower ends to crank arms 21 operated by any suitable power mechanism.

For counter-balancing the receptacle 6 I provide counter-balance weights 22 mounted on slide rods 23 mounted at their lower ends in sockets 24 and connected at their upper ends to sprocket chains 25 passing over sprocket wheels 26 on a shaft 27 mounted at the top of the casing, and having their opposite ends connected at 28 with the tops of the slide rods 18.

Heated air is admitted through the bottom opening 3 by a conduit 29 connected with a suitable heating chamber 30 provided with steam or other heating coils 31. This conduit is provided with a check valve 32 adapted to be closed against back pressure and to be opened under forward pressure against a coil spring 33. If desired, air may be admitted under pressure created by the means of a blower 34 arranged in the conduit.

In operation the goods to be dried are placed in the receptacle 6 which is vertically reciprocated within the casing 1. This receptacle acts somewhat as a piston and on its up stroke will tend to draw the air in through the delivery opening 3, the air being either forced in under pressure of the blower 34 or drawn in merely through the action of the reciprocation of the receptacle

6. On the down stroke of the receptacle the air drawn into the casing 1 is forced up through the opening 8 in the receptacle and through the goods and out through the top 5 of the receptacle, the pressure of the air being sufficient during this movement to raise the goods in the receptacle and "fluff" the goods during its passage therethrough. As the receptacle again rises to draw in a 10 fresh supply of air the goods will tend to drop toward the bottom of the receptacle and due to the cone shape of the bottom thereof tend to crowd toward the inlet opening so as to receive during the next downward movement of the receptacle the full 15 effect of the air passing therethrough.

I have shown heated air being delivered under pressure to the container 1. It will be understood however that the blower 34 20 may, if desired, be dispensed with or the heating of the air may be dispensed with although I have found that the most desirable results are obtained by delivering heated air under pressure.

25. I claim as my invention:

1. In a drier for garments and the like the combination with a receptacle having a foraminous top and a cone shaped bottom provided with a foraminous covered opening, 30 of means for intermittently delivering a blast of air through said receptacle said blast having a tendency to lift the articles contained in the receptacle from the cone shaped bottom.

35. 2. In a drier for garments and the like the combination with a casing, of a receptacle having a foraminous top and a cone shaped bottom provided with a foraminous covered opening reciprocable in said casing 40 and means for admitting drying air to the bottom of said casing, the reciprocal movement of the receptacle in said casing forcing the air up through the receptacle and the garments contained therein.

45. 3. In a drier for garments and the like the combination with a casing, of a receptacle reciprocable in said casing having a foraminous covered opening in the bottom and the top open to the passage of air there- 50 through, said casing having an air inlet opening in the bottom thereof for the ad-

mission of air thereto, the movement of said receptacle in said casing forcing the air through said receptacle and the garments contained therein.

4. In a drier for garments and the like the combination with a casing, of a receptacle having a foraminous covered opening in its bottom and its top open to the passage of air therethrough reciprocable in said casing, said casing having an air inlet to the bottom thereof, a check valve in said air inlet whereby the reciprocation of said receptacle in said casing will draw air into said casing and force the air through the receptacle and the garments contained therein.

5. In a drier for garments and the like the combination with a casing, of a receptacle reciprocable therein and having a cone shaped bottom provided with a foraminous covered opening, the top of said receptacle being open to the passage of air therethrough, said casing having an air inlet passage to the bottom thereof and a check valve for said inlet passage whereby the reciprocation of said receptacle in said casing will draw air into said casing and force the same up through the receptacle and the garments contained therein.

6. In a drier for garments and the like the combination with a casing, of a receptacle reciprocable in said casing and having a cone shaped bottom provided with a foraminous opening, the top of said receptacle being open to the passage of air therethrough and means for causing the intermittent delivery of air under pressure through said bottom opening as the receptacle is reciprocated in said casing.

7. In a drier for garments and the like, the combination with a receptacle having a foraminous top and a bottom provided with a foraminous opening, of means for intermittently delivering a blast of air through said bottom opening of sufficient force to lift the articles contained in the receptacle from the bottom of the receptacle.

In witness whereof I, CHARLES F. GREGG, have hereunto set my hand at Indianapolis, Indiana, this 16th day of March, A. D. 100

one thousand nine hundred and twenty-six.

CHARLES F. GREGG.
